UNITED STATES PATENT OFFICE

2,440,621

FREQUENCY MODULATION

George L. Usselman, Port Jefferson, N. Y., assignor to Radio Corporation of America, a corporation of Delaware

Application April 25, 1944, Serial No. 532,592

7 Claims. (Cl. 179—171.5)

1

This application discloses an improved frequency modulation system. In the improved modulation system of this application, carrier wave energy is generated, stabilized as to mean frequency and deviated in frequency in accordance with signals or control potentials. The signals or control potentials may represent voice, music, code, etc. For example, oscillations generated may be shifted from a first frequency representing a marking condition to a second frequency representing a spacing condition, or deviated in frequency by voice signals.

The means for generating oscillations comprises two tubes each in an oscillation generating circuit comprising a tank circuit regeneratively coupled to the tube electrodes. The tank circuits of the two tubes are tuned to different frequencies separated in the frequency spectrum by the desired amount, the separation being at least as great as the maximum total deviation to be used.

In all of the embodiments a feedback circuit is common to the separate tube generators so that the tubes are entrained to operate at the same mean frequency.

In two embodiments the common feedback path is by way of a crystal which acts as a filter to limit the extent of deviation as well as stabilizing the mean frequency at which the separate oscillators are entrained. In a further embodiment the connections between the tank circuits and the common feedback path include band pass filters which serve to limit the extent of the deviation.

An object of the present invention is to produce frequency modulated oscillations the average frequency of which is substantially constant.

A further object of the present invention is to produce frequency modulated oscillations in which the amount of frequency deviation is limited by the frequency controlling device (crystal or filter).

An additional object of the present invention is to produce frequency modulated oscillations the deviation of which is balanced about the average frequency so that amplitude modulation entailed in producing the deviation is substantially eliminated.

Another object of the invention is to produce frequency modulated oscillations in which the amount of frequency deviation may be adjusted within the limits of the frequency controlling circuits.

The manner in which the above objects and others are attained, and the advantages derived from the attainment of such objects will now be

2

described in detail. In this description reference will be made to the attached drawings wherein Fig. 1 illustrates by wiring diagram the essential features of a frequency modulation system arranged in accordance with my invention. Known refinements may be added to the circuit shown. The circuit shown, however, is substantially complete as to the essential features.

Fig. 2 is a modification of the arrangement of Fig. 1. In Fig. 1, a two-electrode crystal is in a common path between the control grids and cathodes of the tubes. In Fig. 2 a three-electrode crystal is used in a feedback connection between the anode and grid of each tube with a common crystal electrode in the grid side of the circuit.

Fig. 3 is a modification of the embodiment of Fig. 2. In Fig. 3 band pass filters replace the crystal filter of Fig. 2. Band pass filters satisfactory for use in the embodiment of Fig. 3 are shown in Fig. 3a.

Now referring to Fig. 1, V1 and V2 are the oscillation generator and modulator tubes and for the sake of simplicity are shown as triodes but may each have more than three electrodes. The control grids 4 and 6 of these tubes are coupled in parallel by coupling and blocking condensers C to one electrode of the crystal X, the other electrode of which connects the cathodes of the tubes in parallel and to ground.

The anode 10 of tube V1 is connected to a tank circuit L1—C1, the other end of which is grounded by a radio frequency bypassing condenser BP. The inductance of L1 is also connected to the positive terminal of a direct current source, a negative terminal of which is grounded. The anode electrode 12 of tube V2 is similarly coupled to ground and the direct current source by tank circuit C2—L2.

The control grids 4 and 6 are connected respectively by resistances R1 and R2 to the terminals of the secondary winding of a transformer T, the primary winding of which is connected with the signal source A. The resistors R1 and R2 supply negative grid biasing potentials by virtue of grid rectification in the tubes. If more bias is desired a source S may be connected between the mid-point on the secondary winding of transformer T and ground. Radio frequency bypass condensers BP are connected between the lower terminals of resistances R1 and R2 and the cathodes and ground. These condensers shunt the radio frequency potentials around the secondary winding of the transformer T and the source S but are of high impedance to modulating potentials.

The individual oscillators including tubes V1 and V2 and their tank circuits and crystal X may be considered oscillation generators of the tuned grid tuned plate type wherein L1—C1 and L2—C2 are tuned to be slightly inductive at the frequency at which the individual oscillators tend to operate. These oscillators considered separately then generate continuous oscillations.

In the embodiment shown, the tank circuits L1—C1 and L2—C2 are tuned slightly off on opposite sides of the frequency at which the crystal X normally operates. The crystal frequency is assumed in the system to be the mean or carrier frequency at which the system would operate in the absence of control or signal potentials. Say, for example, the tank circuit C1—L1 is tuned to operate at a frequency on one side of the crystal frequency and that tank circuit C2—L2 is tuned to operate at a frequency an equal amount on the other side of the crystal frequency. The amount of shift or spread in the tuning of these tank circuits is determined by the flexibility of the system and by the amount or degree of frequency modulation required. In operation, the tuning of these circuits should be separated in the frequency spectrum an amount at least equal to the total deviation desired.

Since the grids 4 and 6 of the two tubes are connected together and to the crystal X the tubes must operate or oscillate at the same or a common frequency despite the unlike tuning of the tank circuits. Since the tank circuits have unlike tuning the oscillator frequency will swing toward that one of the tubes delivering the most power. If both deliver equal power and the circuits and tubes are substantially alike and balanced, then the system operates at the normal crystal frequency, that is, the carrier frequency. This is so if we assume that the tank circuits are, as stated above, tuned to frequencies symmetrically spaced above and below the crystal frequency. Under the conditions shown, differential modulation of the power delivered by tubes V1 and V2 under control of the signal causes the carrier to be frequency modulated or deviated about the crystal frequency in accordance with the signals. The degree or amount of frequency deviation is proportional to the signal amplitude, and the sense of deviation follows the changes in the signal amplitude with respect to a base value whereat carrier frequency output is produced and the number of frequency variations over a period of time is proportional to the signal frequency.

The output of the frequency modulator may be used directly or may be supplied as illustrated to the input electrodes 20 and 30 of two amplifier tubes V3 and V4 having their anodes coupled in parallel by an output circuit including inductance L3 coupled to output inductance L4. The control grids 20 and 30 are variably tapped on the inductances L1 and L2 so that the desired excitation may be supplied to the control grids of tubes V3 and V4. Chokes CH1 and CH2 block the radio frequency potentials from the direct current grid bias source which is also shunted by radio frequency bypass condensers BP.

The advantage in using a crystal in these modulator circuits is that much more accurate carrier frequency is obtained. That is, the average frequency remains substantially constant. The amount of frequency deviation is limited by the resonance characteristic of the crystal and these circuits are in particular useful for frequency shift keying.

In frequency shift keying the frequency of the

generated oscillations is shifted from a first frequency denoting say marking condition to a second frequency denoting say spacing frequency. The keying is generally done by applying variable amounts of direct current or pulses of A. C. to a tube electrode. In the present case the keying energy is applied differentially. For this purpose a keying-tripping circuit similar to that shown in Fig. 4 of my United States application Serial No. 521,907, filed February 11, 1944, is preferably used and the control grids or the screen grids (when screen grid type tubes are used) of tubes V1 and V2 may be keyed. That is, the tubes V4 and V5 of Fig. 4 of said application and their input and output circuits may be used to key the tubes V1 and V2, Figs. 1, 2 and 3 of this application. To arrange for such use of tubes V1 and V2 when they have screen grid electrodes, the modulation source A (Figs. 2 and 3) is disconnected, leaving the remainder of the control grid circuit unchanged so that the control grids retain their normal bias obtained from source S through the secondary winding of transformer T. The points on the potentiometers 45 and 46 of Fig. 4 of the said application are connected to the screen grid electrodes of tubes V1 and V2 of Figs. 2 and 3, and of Fig. 1, when the same use tubes V1 and V2 of the screen grid type. Keying of the screen grid potentials takes place substantially as described in said application. In the said application the screen grid potentials are varied from a positive value to a negative value at which the tubes V2 and V3 are blocked. In the present case the screen grids are modulated above and below a positive value to swing the frequency of the generated oscillations the desired amount above and below the carrier frequency. The potentials on the screen grids are not, however, varied in the negative direction an amount such as to block oscillation generation. The modulation operation here is more like the operation described and illustrated (Fig. 3) in my U. S. Patent No. 2,326,314, dated Aug. 10, 1943.

To arrange for the keying of tubes V1 and V2 when they are triodes, as in Fig. 1, the grid leads of tubes V1 and V2 are disconnected from the transformer T at points 0—0. The two grid leads are then connected to the two lines of the movable points on potentiometers 45 and 46 of Fig. 4 of my said application Serial #521,907, dated Feb. 11, 1944. When the control grids are to be keyed the adjustments of potentiometers 45—46 and 49 of Fig. 4 of said prior application should be such that these grids are always negative. Keying of the grid potentials take place as described in said application and as described in my U. S. Patent #2,326,314. The keying circuit of said prior application and patent are if desired applied to the generator and modulator tubes V1 and V2 of Figs. 2 and 3 in like manner.

The embodiment of Fig. 2 is in many respects similar to the embodiment of Fig. 1. In Fig. 2, however, oscillators of a different type are used and the oscillators are entrained in a different manner. In Fig. 2, V1 and V2 have their anodes 10 and 12 coupled respectively each to one end of tank circuits C1—L1 and C2—L2. A point on each of the tank circuits is connected to ground by a radio frequency coupling and direct current source bypass condenser BP being thereby connected to the cathodes of tubes V1 and V2.

The grids of the two tubes are tied together as in Fig. 1 by coupling condensers C. In Fig. 2, however, the parallel connected grids are connected to one terminal D of a three-terminal

crystal X, another terminal A of which is tapped through coupling condenser 38 to inductance L1 and the third terminal B of which is tapped through coupling condenser 40 to inductance L2. Note that tube V1 has its anode and grid connected to spaced points on L1, while its cathode is connected to a point intermediate said spaced points so that the tube V1 is an oscillation generator of the modified Hartley type, including in the grid feedback excitation circuit the crystal X. The tube V2, and the described circuits, considered separately is an oscillation generator of a similar type.

The tubes V1 and V2 are of the screen grid type instead of triodes as in Fig. 1, and the screen grids are supplied with direct current operating potentials over bypass condensers BP. The modulation circuit is substantially as shown in Fig. 1, and will not be discussed herein. When voice or similar signals are used they are applied at A to transformer T. When frequency shift signalling is to be carried out a tripping-keying circuit as described above may be connected to the control grids or screen grids.

The three-electrode crystal X which has a filtering action has its common electrodes D connected to the grids of tubes V1 and V2, while the electrode A is tapped on tank circuit coil L1 and electrode B is tapped on tank circuit coil L2, as described above. Neutralizing condenser N1 is connected between the anode end of tank circuit coil L1 and the crystal filter electrode D, while neutralizing condenser N2 is connected between the anode end of tank coil L2 and the crystal filter electrode B.

Here, as in Fig. 1, the tank circuits C2—L2 and C1—L1 are tuned to opposite sides of the normal frequency of crystal filter X and if symmetrical operation is desired, which is preferable, they are tuned to frequencies which differ from the crystal frequency in opposite direction by equal amounts. The filter electrode A and neutralizing condenser N1 are tapped symmetrically on each side of the point at which L1 is grounded. This point may be the center point of the tank circuit. Neutralizing condenser N2 and electrode B are also symmetrically tapped with respect to the point on inductance L2 connected to ground for R. F. voltages by the condenser BP. The neutralizing condensers N1 and N2 are adjusted to just balance the capacity effect of each half of the crystal filter electrodes so that when the crystal is not oscillating the grids 4 and 6 are in effect connected to a neutral point and no unwanted oscillations can reach the grids from the anode tank circuits. It is also essential that for best operation both sides of the modulator be substantially identical except for the equal and opposite tuning adjustments of the tank circuits. When the electrodes of the tubes are charged oscillations are generated in a well known manner, the crystal oscillates and feedback takes place therethrough, as described hereinbefore.

Under these conditions differential modulation of the potentials on the control grids of tubes V1 and V2 by the signals causes the frequency of the entrained oscillators to vary in accordance with signals. The tube delivering the most power will cause a carrier frequency shift in the direction of the frequency for which the tank circuit of that tube is tuned. This shift will be substantially proportional to the differences of power delivered by the tubes V1 and V2.

The crystal filter limits the band in which the

modulator can operate. When no signal modulation is present and at instances when the modulation potentials are equal or their differences are zero, then there remains only the carrier frequency which is substantially in the middle of the filter pass band because the filter characteristic is shaped for this purpose. This is a balanced type of frequency modulator as is the embodiment of Fig. 1, and the amplitude modulation is balanced out and does not appear in the output.

The main purpose of using the crystal is to maintain a substantially constant carrier frequency. However, this limits the band width of frequency modulation. This seems to be a fundamental fact. This type of modulator (using a crystal for frequency control) is useful where frequency shift keying is used because usually in this case a frequency shift of only a few hundred cycles is desired. In order to use frequency shift keying the control grids or screen grids may be keyed differentially by means of the keying-tripping circuit such as that shown in Fig. 4 of my U. S. application Serial #521,907, filed February 11, 1944. This latter circuit can supply either positive or negative keying bias as desired depending on the adjustments.

The embodiment of Fig. 3 is essentially as disclosed in Fig. 2, except for the following main differences.

Band pass filters designated by rectangles F1 and F2 and are in this embodiment connected to the capacitive branch of each of the tank circuits. L1 is now shunted by condensers C1, C3 and C5, while L2 is shunted by condensers C2, C4 and C6. The band pass filter F1 has its input between condensers C1 and C3, while the neutralizing condenser N1 is connected at the junction point between condensers C3 and C5. The band pass filter F2 has its input between condensers C2 and C4, while neutralizing condenser N2 is connected between condensers C4 and C6. C3 and C4 are used as a convenient means for adjustment of the excitation coupling, and condensers C1 and C5 and C2 and C6 are connected mechanically for symmetrical simultaneous adjustment. The band pass filters F1 and F2 may be alike or they may merely have overlapping characteristics in the region of the carrier frequency. These filters may be of any desirable type, such as a single crystal filter as shown in Fig. 1, or they may be a multiple type crystal filter as shown in Fig. 2, or they may consist of a combination of coils and condensers arranged to have a band pass characteristic. In Fig. 3a, I have shown filters satisfactory for use in the embodiment of Fig. 3. In Fig. 3a, L6 and C6 and L'6 and C'6 are the filter elements. N1 and N2 are the neutralizing condensers. The condensers Q are coupling condensers used for coupling the filters and neutralizing condensers to a common point and thence to the condenser C. Now N1 and N2 control the amount of feedback to the grids. If adjustment for complete neutralization is made there would be no feedback. Under or over-neutralization permits feedback as desired. If crystal filters are used as in Figs. 2 and 3, neutralization stops feedback through the crystal holder capacity thereby allowing feedback only through the oscillating crystal.

I claim:

1. In a timing modulation system of the type comprising two tubes, each having a plurality of electrodes, a tank circuit tuned to a first fre-

quency regeneratively coupling the electrodes of one tube in an oscillation generating circuit, said connections including a feedback excitation circuit between the anode and control grid of the tube, a second tank circuit tuned to a second frequency coupling the electrodes of the other tube in a regenerative oscillation generating circuit, said last named oscillation generating circuit including a feedback excitation circuit between the anode and control grid of the second tube, a band pass filter which passes a frequency spectrum including said first frequency and half of the band between said first and second frequency in said first feedback circuit, a band pass filter which passes a band of frequencies including said second frequency and half of the band between said first and said second frequency in said second feedback connection, and means for differentially controlling the gains of said tubes in accordance with signals.

2. In an oscillation generator, two electron discharge devices each having an anode, a cathode and a control grid, two circuits each comprising capacity and inductance in parallel tuned one to a frequency above, the other to a frequency below the desired mean operating frequency, a coupling between the anode of one tube and one tuned circuit, a coupling between the anode of the other tube and the other tuned circuit, means for providing regenerative feedback between the anode and grid of each tube whereby each tube is connected in an oscillation generating circuit, said means comprising series coupling condensers substantially directly coupled between the control grids of said tubes, a feedback coupling between one parallel tuned circuit and the junction point between said series condensers and a feedback coupling between the other parallel tuned circuit and the junction point between said series condensers, said feedback couplings having a portion in common which common portion with said substantially direct coupling between the grids of the tubes entrains said oscillation generating circuits so that they operate at a common frequency, and a wave filter in said generating circuits which passes a band of frequencies centered on a frequency intermediate the two frequencies to which said parallel circuits are tuned.

3. An oscillation generating system as recited in claim 2 wherein the filter is a band pass filter in the connection between the anode and grid of each tube.

4. An oscillation generating system as recited in claim 2 wherein the wave filter is in the feedback couplings and comprises a three-electrode crystal with one electrode coupled to the grids

of both tubes, the second electrode coupled to one parallel tuned circuit, and the third electrode coupled to the other parallel tuned circuit.

5. In a signalling system, two electron discharge devices each having an anode, a cathode and a control grid, two circuits each comprising capacity and inductance in parallel, tuned one to a frequency above, the other to a frequency below the desired mean operating frequency, a coupling between the anode of one tube and one tuned circuit, a coupling between the anode of the other tube and the other tuned circuit, means for providing regenerative feedback between the anode and grid of each tube whereby each tube is connected in an oscillation generating circuit, said means comprising series coupling condensers substantially directly coupled between the control grids of said tubes, a feedback coupling between one parallel tuned circuit and the junction point between said series condensers and a feedback coupling between the other parallel tuned circuit and the junction point between said series condensers, said feedback couplings having a portion in common, which common portion with said substantially direct coupling between the grids entrains said oscillation generating circuits so that they operate at a common frequency, a wave filter in said generating circuits which passes a band of frequencies centered on a frequency intermediate the two frequencies to which said parallel circuits are tuned, and a source of modulating potentials coupled differentially to corresponding electrodes in said tubes.

35. 6. A signalling system as recited in claim 5 and wherein said wave filter comprises a band pass filter in each of said feedback couplings.

7. A system as recited in claim 5 wherein the wave filter is a three-electrode crystal with one electrode coupled to the grids of both tubes, the second electrode coupled to one parallel tuned circuit, and the third electrode coupled to the other parallel tuned circuit.
